Dec. 1577

David Foyer, of Dover, N. H.,
Assignor to
Abraham Folsom & Son, of Boston, Mass.
Letters Patent No. 1577, dated May 13, 1862,

The schedule referred to in these Letters Patent and making part of the same.

To all Persons to whom these Presents shall come:

Be it known that I,
David Foyer, (an alien who has resided the past year in the United States, and now resides at Dover, in the County of Strafford and State of New Hampshire,) have invented or produced a new and original design, pattern, print or picture, to be either worked into or worked on, or painted or printed or otherwise fixed on any article of manufacture.

My design or pattern being especially intended for painted floor cloths or carpets, and I do hereby declare the same is represented in the accompanying drawings.

The main body of the design consists of four octagonal panels A, arranged in contact with one another and about an ornamented square B. Each panel is furnished with a representation of a collection C, of flowers or leaves, two of the panels on two opposite sides of the square having representations of cherries D, or fruit imposed on or among the leaves, the whole being as exhibited in the drawing.

I claim the said design, pattern or print as my invention or production.
